US00D915423S

(12) **United States Design Patent** (10) **Patent No.:** **US D915,423 S**
Kozlova et al. (45) **Date of Patent:** **** Apr. 6, 2021**

(54) **DISPLAY SCREEN OR PORTION THEREOF WITH GRAPHICAL USER INTERFACE**

(71) Applicant: **Juniper Networks, Inc.**, Sunnyvale, CA (US)

(72) Inventors: **Yelena Kozlova**, Sunnyvale, CA (US); **Amol Sood**, Cupertino, CA (US); **Johan Andersson**, San Francisco, CA (US); **Lyubov Nesteroff**, Pleasant Hill, CA (US)

(73) Assignee: **Juniper Networks, Inc.**, Sunnyvale, CA (US)

(**) Term: **15 Years**

(21) Appl. No.: **29/695,982**

(22) Filed: **Jun. 24, 2019**

(51) LOC (13) Cl. **14-04**

(52) U.S. Cl.

USPC **D14/485**

(58) **Field of Classification Search**

USPC D14/485-495

CPC G06F 3/048-04897

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outermost broken lines in the FIGURE shows a display screen or a portion thereof. The remaining broken lines, including all of the text shown, show portions of the graphical user interface. None of the broken lines form part of the claimed design.

1 Claim, 1 Drawing Sheet
